UNITED STATES PATENT OFFICE.

FERDINAND BUCHHOP, OF NEW YORK, N. Y., ASSIGNOR TO THE MEYROWITZ MANUFACTURING COMPANY, A CORPORATION OF NEW JERSEY.

CUT-OUT.

SPECIFICATION forming part of Letters Patent No. 766,490, dated August 2, 1904.

Application filed October 29, 1903. Serial No. 178,994. (No model.)

To all whom it may concern:

Be it known that I, FERDINAND BUCHHOP, a citizen of the United States, residing at the city of New York, in the borough of Brooklyn 5 and State of New York, have invented certain new and useful Improvements in Cut-Outs, of which the following is a full, clear, and exact description.

This invention relates to electric cut-outs, 10 the object being to provide a simple and compact structure operated by a push-button or plunger and especially adapted for insertion in or combination with an incandescent-lamp socket, the cut-out being used by me in such 15 a location for the purpose of controlling a tap-circuit taken from the main circuit of the socket; but it will be understood that the improved cut-out may be used under various conditions and that the invention resides in 20 the construction itself and not in any special combination with other devices or apparatus.

My improved cut-out comprises, essentially, 25 a fixed plate, opposite and parallel to which is arranged a rotary disk carrying on the surface 30 opposed to the plate a pair of contacts adapted when the disk is in one position to make contact with said plate and when in another position to straddle said plate without making contact therewith. The disk is provided with a series 35 of ratchet-teeth, and immediately adjoining these and in a parallel relation is a flat plate acting as a plunger by manual manipulation, said flat plate having two dogs, one of which is adapted to engage one of the ratchet-teeth 40 of the disk during the forward movement of the plunger, while the other dog engages another of the ratchet-teeth during the return movement of the plunger. These two engagements cause the disk to be rotated each 45

a one-eighth turn, so that a movement of the plunger inward and outward rotates the disk a quarter-turn and either completes or breaks the circuit between the disk and fixed plate. Auxiliary to these devices is a spring combined and arranged in such manner as to keep the plunger to its work and yet permit it to yield to avoid interference with the ratchet-teeth during rotary motion of the disk. These points, as well as all other fea-

tures of the construction, will be described 50 hereinafter with reference to the accompanying drawings, in which—

Figure 1 is a side elevation of the structure containing my cut-out. Fig. 2 is a section of the same. Fig. 3 is a plan of one half of 55 the frame, showing the fixed terminal. Figs. 4 and 5 are plans of the second half of the structure containing the movable parts of the cut-out and showing them in two different positions. Fig. 6 shows side and plan 60 views of the plunger. Fig. 7 is an edge view and top plan of the rotary disk. Fig. 8 is a section and bottom plan of the rotary disk.

The parts of my cut-out are housed within a block of hard rubber or other suitable insulating material A. This block is made in two parts *a* and *a'*, each being substantially a disk having a diametrical raised portion *a*² across one face, thus leaving a segmental opening *a*³ on each side of the cylinder formed by 65 the joining of the two disks. The disks are held together by bolts *a'*, one on each side of the center.

In the disk *a* there is an axial metal stud *b*, 70 having attached to its outer end a contact-head *b'* and at its inner end a cross-bead *b*² in the form of a plate, each end of which is sector-shaped and of slightly less than ninety degrees in size. This plate is a fixture in a circular depression *b*³ and leaves open sector-shaped spaces *b*⁴ at opposite sides. This plate *b*² is a circuit terminal or contact through 75 which the current may be led to the head *b'* and to an extension *b*⁵ for any desired arrangement of circuits.

In the disk *a'* there is a contact-head *c*, exposed outside, which is attached to the end of an axial screw *c'*, around the head of which fits a rotary disk *e*, which stands parallel to the fixed plate *b*² and concentric with the stud *b*. The upper surface of this disk *e* is provided at diametrically opposite points with two lugs *e*², shaped similar to ratchet-teeth, but without their function. These teeth are adapted to make contact simultaneously with the opposite ends of the plate *b*² when the disk is rotated to bring this connection about; but when the disk is rotated ninety degrees 85

from the position of contact the lugs project into the spaces b^4 b^5 , and thus break the circuit. The under side of disk e is provided with four ratchet-teeth e^2 , arranged in a circle at the outer edge of the disk and all pointing in the same direction. Immediately beneath the disk is a flat plate f , serving as an operating-plunger, said plate having a slot f^1 , through which the screw c' passes, and having two dogs f^2 and f^3 , extending upward on each side of the slot and in a position to engage the ratchet-teeth e^2 on the disk. The plate f extends radially outward through an opening in the side of the block A and carries at its outer end a push-button f^4 . A spring g is provided between the head of the push-button and the block A, having a tendency to force the button outward. Beneath the plate f is a disk i upon the stud c' , which disk is forced against plate f by a spring j , surrounding the stud c' for the purpose of holding plate f up against disk e , so that its dogs f^2 and f^3 will engage with the ratchet-teeth. At the same time the disk is free to tip in any direction, thus permitting the plate f to yield when the ratchet-teeth of the disk e ride over the dogs of the plate, as will be hereinafter described. It will be seen that when disk e and plate b^2 are in contact a circuit is closed from contact c through the stud c' , disk e , plate b^2 , from which it branches, one branch leading through the stud to the button b^1 and the other through the extension b^5 .

The operation is as follows: Referring more particularly to Figs. 4 and 5, it will be seen that the plunger f is extended outward in Fig. 4. This is the normal position, during which the circuit may be either open or closed. We will assume that at the present time the lugs e^1 of disk e are occupying the spaces b^4 , the circuit being thus open. By pressing the push-button f^4 and forcing the plunger inward the dog f^2 engages with a ratchet-tooth e^2 and the disk is rotated one-eighth of a turn, during which motion a ratchet-tooth e^2 on the opposite side of the disk slides over the dog f^3 and assumes the position shown in Fig. 5, where the dog will engage with its shoulder upon the return movement of the plunger. The plunger now being released, spring g acts and forces it outward, during which movement dog f^3 aforesaid engages with ratchet-tooth e^2 and moves the disk another one-eighth turn in the same direction as before. This completes a quarter-turn of the disk and carries the two lugs e^1 , respectively, into contact with the ends of the plate b^2 and closes the circuit. It will be seen that dur-

ing the movement of the disk to carry the ratchet-teeth backward over the dog it is necessary for either the dog or the plate f to yield or tip. This is permitted by the yielding support beneath the plate. It will be seen that the to-and-fro excursion of the plunger completes either a make or break of the circuit.

It is obvious that this structure may be used also for a double-pole switch by insulating the lugs e^1 from each other and insulating the ends of the plate b^2 from each. My invention is therefore not limited in respect to the number of circuits or lines controlled.

Having described my invention, I claim—

1. In an electric cut-out, the combination with a fixed plate forming one terminal of the circuit, a rotary plate arranged parallel thereto and adapted to make and break contact therewith, in combination with a plunger adapted to impart two movements in the same direction to the rotary plate by two successive opposite movements of its own, substantially as described.

2. In a cut-out, the combination of a fixed contact-plate, a rotary disk carrying contact-points adapted to engage and disengage with the plate, ratchet-teeth arranged in a concentric circle on said disk and a reciprocating plunger provided with two dogs adapted to engage respectively and alternately with ratchet-teeth on opposite sides of the center of the disk.

3. In a cut-out, the combination of a fixed contact-plate, a rotary disk carrying contact-points adapted to engage and disengage with the plate, ratchet-teeth arranged in a concentric circle on said disk, a reciprocating plunger provided with two dogs adapted to engage respectively and alternately with ratchet-teeth on opposite sides of the center of the disk and a spring tending to hold the plunger in engagement with the ratchet-teeth.

4. The combination of the fixed contact-plate b^2 , the rotary contact-disk e having ratchet-teeth, a reciprocating plate provided with a slot through which the axis of the disk passes, two dogs carried by said plate adapted to engage the ratchet-teeth alternately and a spring adapted to move the reciprocating plate in one direction.

In witness whereof I subscribe my signature in presence of two witnesses.

FERDINAND BUCHHOP.
